COMBINED ROBE RAIL AND RECEPTACLE

Carl F. Schlegel, Rochester, N. Y., assignor to The Schlegel Manufacturing Company, Rochester, N. Y., a corporation of New York

Application May 4, 1934, Serial No. 723,955

18 Claims. (Cl. 224—29)

The present invention relates to a combined robe rail and receptacle and has for its object to provide an improved supporting device of this class which can be conveniently employed as a holding means for robes, shawls, and various kinds of wearing apparel, as well as various articles which can be readily placed within the receptacle and removed therefrom when desired.

5 A further object of the invention is to provide an improved device of the class described designed for application to seat backs and other supporting structures, and which is of simple and durable construction, ornamental and attractive in appearance, and designed to maintain its 10 shape and to lend itself to various usages as an article carrying device.

15 A further object of the invention is to provide an improved robe rail preferably of the flexible type adapted for attachment to a suitable support to occupy a substantially horizontal position thereon, in combination with a receptacle connected with and depending from the robe rail and adapted to receive and support various articles without interfering with the use of the 20 robe rail as a robe supporting device.

25 A further object of the invention is to provide in combination with a robe rail, an article holding receptacle, together with improved means for connecting the receptacle with the robe rail.

30 To these and other ends the invention resides in certain improvements and combinations of parts, all as will be hereinafter more fully described, the novel features being pointed out in the claims at the end of the specification.

35 In the drawing:

Fig. 1 is a plan view of a combined robe rail and receptacle embodying one form of the invention;

Fig. 2 is a side elevation of the same;

40 Fig. 3 is a fragmentary view in elevation drawn to an enlarged scale and illustrating the manner of connecting the receptacle supporting means with the robe rail;

45 Fig. 4 is a fragmentary view of a portion of the robe rail drawn to an enlarged scale and showing a portion of the resilient means contained therein for preventing sagging of the same;

50 Fig. 5 is a transverse sectional elevation drawn to an enlarged scale and taken on line 5—5 of Fig. 2;

Fig. 6 is a plan view of a modified form of the combined robe rail and receptacle;

Fig. 7 is a side elevation of the same, and

55 Fig. 8 is a transverse sectional elevation drawn

to an enlarged scale and taken on line 8—8 of Fig. 7.

The same reference numerals throughout the several views indicate the same parts.

The present invention relates to article holding means of the type which is particularly adapted for use in different kinds of vehicles or conveyances of the passenger carrying type where it is desired to provide means for supporting, in a comparatively small space, various articles such as small packages or bundles, along with wearing apparel, lap robes, and other articles, which it may be desired to carry along when traveling from time to time.

To this end I have provided an improved article holding device which can be attached to the back of a seat or to a wall or other support in different types of vehicles, but which is particularly adapted for use on the backs of the seats of automobiles such, for example, as the front seat or others having free space at the rear thereof. The device comprises generally a flexible robe rail having its ends adapted for attachment to a seat back and carrying a depending receptacle, preferably one of a bag-like type having its ends connected with the ends of the robe rail and its rear portion also connected therewith at points intermediate the ends thereof, while its front portion is supported by a flexible cord-like member extending longitudinally of the robe rail and connected with the ends of the latter, said member being preferably formed of resilient material so that it will snap back into position upon release, after being pulled outwardly to enlarge the opening between said front and rear portions to facilitate insertion of the articles within the receptacle.

Referring to the drawing, 10 designates a support such as a seat back or other structure to which the robe rail, indicated generally at 11, 40 is attached, as by means of the brackets 12 or other suitable securing devices. The robe rail is preferably of the flexible type and in the present disclosure is formed by twisting together a plurality of cords or strands 13 formed of any suitable material. The ends of the twisted cords are preferably unraveled as indicated at 14 and extended through the ring-like portions 15 of the brackets 12 to form loops at the ends of the robe rail which may be secured in any suitable manner such, for example, as by wrapping or winding about the loops one or more strong threads or strands as indicated at 16 in Fig. 3. However, it will be understood that the ends of the flexible robe rail may be formed or constructed in a dif-

ferent manner from that shown and suitably connected with the ring-like portions of the brackets 12 with other suitable securing devices.

The brackets 12 may be connected with the support 18 by any suitable means such, for example, as the screws 17. The brackets are preferably constructed and applied to the support or seat back in a manner to maintain the robe rail in spaced relation thereto, thus facilitating gripping of the same and the application of lap robes, shawls, and other articles of wearing apparel to the robe rail.

Furthermore, means is provided for preventing sagging of the robe rail and for returning it to normal position when deflected therefrom, this means preferably comprising a spring 18a, of the closely coiled type, Fig. 4, which lies within and extends longitudinally of the robe rail and which is of a length and capacity sufficient to support it in the desired horizontal position.

The receptacle, which is connected with the robe rail, may be of any preferred type and is preferably supported in depending relation thereon. The receptacle may be formed of any suitable material, such, for example, as cloth, netting, or other woven or fabric-like material. In the present disclosure the receptacle, indicated generally at 18, is formed of interwoven or connected strands which may comprise twisted threads of silk or other fibrous material connected in a manner to afford a receptacle which is both attractive in appearance and efficient in service. The individual strands forming the receptacle are best indicated at 19 in Fig. 3, and at the ends of the receptacle such strands are crowded together as at 19a and secured to the ends of the robe rail by any suitable means such as the wrapping or binding thread 16 for securing the looped portions 14 of the robe rail one upon another.

The front portion of the receptacle is supported by a flexible cord-like member indicated generally at 20 and preferably formed of resilient material such as rubber, shown in section at 20a in Fig. 5, said member having a protecting cover thereon which may be of braided or other suitable material.

The strands 19 extending along the top of the front portion of the receptacle are connected with the cord-like member 20 by means of the loops or loop-like portions 21 while the corresponding strands of the rear portion of the receptacle are connected with the robe rail 11 by similar loops or loop-like portions 22, Figs. 3 and 5, the loops being spaced at the desired intervals, preferably throughout the length of the robe rail and said supporting member as indicated in Figs. 1 and 2.

The cord-like member 20 has its end portions 23 positioned upon the ends of the flexible robe rail as indicated by dotted lines in Fig. 3, said end portions being preferably extended through the ring-like members 15 of the brackets 12 and turned back upon the robe rail ends so that they engage said ends at opposite sides thereof upon which they are secured preferably by the binding means 16, although if desired they may be secured by any other suitable means.

It will be seen therefore that the strands 19a at the ends of the receptacle 18 and the end portions 23 of the cord 20 are firmly and securely connected with the ends of the robe rail whereby the weight of the articles placed within the receptacle will be carried by said robe rail and the brackets or fixtures 12 with which it is connected. A portion of the weight of the articles will, however, be transmitted to the robe rail at

various points between its ends by the loops or rings 22 connecting the rear portion of the receptacle with the robe rail as shown in Figs. 3 and 5.

The ends of the robe rail and the portions of the receptacle attached thereto are provided with protecting covers 24 which may be crocheted or otherwise formed over and secured upon said robe rail ends to provide a proper finish for the same.

When it is desired to place articles within the receptacle the resilient cord-like member 20 may be grasped and pulled outwardly to widen the opening at the top of the receptacle whereby to permit the articles to be deposited therein, after which when the cord-like member is released, it will, through the resiliency of the material thereof, be returned to normal position or substantially to the position shown in Fig. 5.

In the form of the device as shown in Figs. 1 to 5 of the drawing, the robes or articles of wearing apparel will be placed upon the robe rail in the usual manner and supported thereby independently of the receptacle depending therefrom, or in other words, the weight of such articles will be carried entirely by the robe rail without any strain on the receptacle.

In the modification shown in Figs. 6 to 8, inclusive, the receptacle and supporting brackets for the robe rail are substantially the same as the corresponding parts of Figs. 1 to 5, inclusive, and have therefore been given the same reference characters. However, the robe rail connected with said brackets comprises similar front and rear cord-like members or sections 25, each formed preferably by twisting together a plurality of strands 25a, shown in section in Fig. 8. The ends of the cord-like members 25 may be connected with the rings or ring-like members 15 of the brackets 12 in any suitable manner as, for example, by unraveling said ends and looping and securing them upon said ring-like members in the manner shown in Fig. 3. However, any other suitable method may be employed for connecting said ends with the brackets.

Furthermore, the strands 19a at the ends of the receptacle shown in Figs. 6 to 8, inclusive, are preferably crowded together and secured upon the ends of the cord-like members 25 by any preferred means or in a suitable manner, said strands being concealed by the covers 26, which are similar to the covers 24 shown in Figs. 1 and 2.

The strands 19 at the upper edges of the front and rear portions of the receptacle shown in Figs. 7 and 8 are connected with the front and rear sections of the robe rail by means of loops or loop-like portions 27 similar to those shown at 22 in Figs. 3 and 5, so that the weight of the articles placed within the receptacle is distributed equally between the parallel sections 25 of the robe rail and the oppositely disposed brackets 60 with which said sections are connected.

The weight of the robes, coats, and other articles of wearing apparel placed upon the robe rail of the modified device shown in Figs. 6 to 8, inclusive, will also be distributed equally between the robe rail sections 25, independently of the package carrying receptacle depending therefrom.

I claim:

1. In a device of the class described, the combination of a flexible robe rail adapted for attachment to a support, an article holding receptacle extending longitudinally of the robe rail and having means connecting it therewith for support thereby, and a resilient element secured within 75

- the robe rail for returning it and the receptacle to normal position when deflected therefrom.
2. In a device of the class described, the combination of a robe rail, securing members on the ends of the robe rail for connecting it with a support, an article holding receptacle beneath the robe rail including a flexible supporting member extending longitudinally of the robe rail and having its ends connected with the securing members, portions of said flexible supporting member adjacent its ends being positioned upon the ends of the robe rail, and means for securing said portions upon said robe rail ends.
3. In a device of the class described, the combination of a robe rail, securing means on the ends of the robe rail for connecting it with a support, an elongated receptacle having opposite side portions extending longitudinally of the robe rail, means serving to connect one of said side portions with the robe rail at intervals between the ends of the latter, a cord-like member connected with and forming a support for the other of said side portions and means connecting the ends of said cord-like member and the robe rail with said securing means.
4. In a device of the class described, the combination of a robe rail having means on the ends thereof for securing it upon a support, an elongated receptacle having spaced side portions extending longitudinally of the robe rail, a plurality of securing parts disposed on the robe rail and connecting one of said side portions therewith at points between said securing means, and supporting means for the other side portion of the receptacle connected with the robe rail adjacent the ends thereof, independently of the supporting parts of the first mentioned side portion of the receptacle.
5. In a device of the class described, the combination of a robe rail having means at its ends for securing it upon a support, a receptacle beneath the robe rail having opposite side portions extending longitudinally of the robe rail, a plurality of supporting members for one of said side portions encircling the robe rail, a flexible cord extending longitudinally between the ends of the robe rail and having its ends positioned upon said robe rail ends, means serving to bind said ends upon the robe rail, and supporting means for the other of said side portions connected with said flexible cord.
6. In a device of the class described, the combination of a robe rail having means on the ends thereof for securing it upon a support, a receptacle beneath the robe rail having opposite side portions extending longitudinally of the robe rail, said receptacle formed of netting and one of the side portions having a plurality of loop-like members connecting it with the robe rail, a flexible cord extending longitudinally of the robe rail between the ends thereof and having its ends connected therewith, and loop-like supporting members for the other side portion of the receptacle surrounding said flexible cord at intervals between the ends thereof.
7. In a device of the class described, the combination of a robe rail having parts at its ends for securing it upon a support, an article holding receptacle extending longitudinally beneath the robe rail and having its ends secured upon said parts, and means connecting the receptacle with the robe rail intermediate the ends of the latter.
8. In a device of the class described, the combination of a robe rail having parts on its ends for securing it upon a support, an article holding receptacle extending beneath the robe rail and formed of a plurality of connected strands, the strands at the ends of the receptacle being bunched together and positioned upon the end portions of the robe rail adjacent said securing parts, means connecting said bunched strands with the end portions of said robe rail, and means connecting one side of the receptacle with said robe rail intermediate the ends of the latter.
9. In a device of the class described, the combination of a robe rail having parts at its ends for securing it upon a support, an article holding receptacle beneath the robe rail having opposite side portions extending longitudinally of the robe rail, said receptacle formed of interwoven strands and the strands at the ends of the receptacle being bunched together and positioned upon the end portions of the robe rail adjacent said securing parts, a cord extending longitudinally of the robe rail and connected with and adapted to support one of the side portions of the receptacle, said cord having its ends positioned upon said end portions of the robe rail, and means serving to secure the ends of said cord and the strands positioned upon the end portions of the robe rail thereon.
10. In a device of the class described, the combination of a seat back, a flexible robe rail connected with said seat back, an article holding receptacle formed of flexible material and extending longitudinally beneath the robe rail and connected therewith, and resilient means associated with the robe rail and receptacle for returning the latter to normal position when released after deflection from said position.
11. In a device of the class described, the combination of a supporting structure, a robe rail connected with said structure to occupy a substantially horizontal position thereon, an article holding receptacle extending beneath the robe rail and including front and rear portions, means connecting said rear portion with the robe rail, and a supporting member independent of said means connected with the front portion of the receptacle and extending longitudinally of the robe rail and connected with the supporting structure.
12. In a device of the class described, the combination of a supporting structure, a flexible robe rail, an article holding receptacle, means connecting the receptacle with the robe rail, means connecting the ends of the robe rail with the supporting structure, and resilient means extending longitudinally of the robe rail and operating to return it to normal position when released after deflection from said position.
13. In a device of the class described, the combination of a supporting structure, a flexible robe rail, parts connecting the opposite ends of the robe rail with the supporting structure, an article holding receptacle extending beneath the robe rail and including a flexible vertically disposed front portion, a resilient cord-like supporting member for said front portion extending longitudinally of the robe rail between the ends thereof and having its end portions disposed on said robe rail ends and connected with said parts, and means extending inwardly of said parts and serving to secure the ends of said cord-like member on the ends of said robe rail.
14. In a device of the class described, the combination of a supporting structure, a flexible robe rail connected therewith to occupy a substantially horizontal position thereon, a resilient element associated with the robe rail adapted to re-

turn it to normal position when deflected therefrom, and an article holding receptacle extending longitudinally beneath the robe rail and connected therewith, said receptacle including a flexible vertically extending front portion and a resilient cord-like supporting member for said front portion extending longitudinally of the robe rail and having its ends connected therewith, said resilient cord-like member when deflected outwardly by a pull thereon operating to move the front section of the receptacle outwardly therewith and serving to return the same to normal position upon release of said cord-like member.

15. In a device of the class described, a flexible robe rail, securing devices for attaching the robe rail to a support, said devices having openings through which the ends of the robe rail are looped, a receptacle formed of flexible material and having supporting end portions positioned upon the looped ends of the robe rail, and means serving to secure said end portions of the receptacle upon the looped ends of the robe rail.

20. In a device of the class described, a flexible robe rail formed of a plurality of twisted strands, securing devices for attaching the robe rail to a support, said devices having openings through which the end portions of the robe rail are looped, a resilient member concealed within the strands of the robe rail, a receptacle formed of fabric like

material and having end portions positioned upon the looped end portions of the robe rail, and means connecting the end portions of the receptacle with the looped portions of the robe rail, said resilient member serving to return the robe rail to normal position when released after deflection from said position.

17. In a device of the class described, the combination of a robe rail, devices with which the opposite ends of the robe rail are connected for attachment to a support, an article holding receptacle extending longitudinally of the robe rail and having end supporting portions positioned upon the ends of the robe rail, and one or more securing strands wrapped about the ends of the robe rail and the end portions of the receptacle and securing them one upon another.

18. In a device of the class described, a flexible robe rail, devices connected with the robe rail for attaching it to a support, a receptacle having opposite side portions one including a flexible cord extending longitudinally of the robe rail and having its end portions disposed on the ends of the robe rail, and securing strands wrapped about the ends of the robe rail and the end portions of the cord and serving to bind said robe rail ends and the end portions of the cord together.

CARL F. SCHLEGEL.
